UNITED STATES PATENT OFFICE.

DAVID HYAMS, OF NEW YORK, N. Y.

DUPLICATING-MACHINE.

1,168,640.

Specification of Letters Patent. Patented Jan. 18, 1916.

Application filed May 15, 1914. Serial No. 838,628.

To all whom it may concern:

Be it known that I, DAVID HYAMS, a citizen of the United States, and a resident of New York city, county and State of New York, have invented certain new and useful Improvements in Duplicating-Machines, of which the following is a specification.

This invention relates to a duplicating machine more particularly to a machine for 10 making duplicate copies from a gelatinous material adapted to absorb an original writing in ink.

To the accomplishment of the above objects and to such others as may hereinafter 15 appear, the invention comprises a rotary drum for holding a sheet of gelatinous material, means for pressing sheets of paper against said gelatinous material and means for stripping the sheets of paper from said 20 gelatinous material.

Referring to the drawings, Figure 1 is a side elevation of a machine embodying my invention. Fig. 2 is a top view of Fig. 1. Fig. 3 is a detail view of the drum. Fig. 4 25 is a detail view partly in section on an enlarged scale of the presser roller and stripping rollers.

In the drawings: A designates the base of the machine, and B the frames or stands 30 which support the drum C, so that it can be rotated by means of a removable crank D.

In the present instance and according to the present invention the drum C is arranged to detachably hold on its outer surface a sheet E coated on one side with a gelatinous material for absorbing an original writing in ink and imparting said writing to sheets of paper, whereby a number 40 of copies of an original writing is produced.

The ends of the gelatinous sheet E are preferably not provided with gelatinous material, the ends of the sheet being secured to the surface of the drum C by means of 45 clamps G and H.

The clamp G which secures one end of the gelatinous sheet E to the drum C is, in the present instance, preferably made of spring metal and extends across the face of 50 the drum. The ends of the clamp G are bent over the sides of the drum and secured in place by means of set screws K which engage the slots L in the plates M situated on opposite sides of the drum. The screws 55 K can be set any place along the slots L to

adapt the clamp G to varying lengths of sheets.

The clamp H which holds the other end of the gelatinous sheet E to the drum C is also preferably made of spring metal and extends across the face of the drum, the ends of the clamp being bent over the sides of the drum and secured in place by means of set screws N.

The clamp H is provided in the present 65 instance with a feeding member O the object of which will be described later. In the present instance the feeding member O is made integral with one side of the clamp H and when in normal position it assumes the 70 raised position shown in Fig. 1, and in dotted lines in Fig. 4.

The standards B are provided with bearing supports P in which is adjustably mounted the spring pressed roller Q which 75 is adapted to press blank sheets of paper against the surface of the gelatinous sheet E so that the blank sheets will take the ink impression contained on the gelatinous sheet E.

The standards B are also provided with bracket members R which support a feeding table S upon which blank sheets are placed to be fed into the machine, the table S being preferably placed adjacent the 85 lower edge of the roller Q as shown in Fig. 1.

The drum C of the machine is placed in its starting position by turning the crank D until the spring pressed roller Q rests 90 upon the feeding member O thereby compressing the same as shown in Fig. 4. In order to hold the drum in its normal starting position the top of the feeding member O is provided with a concave projection T 95 as shown in Fig. 4. The projection is easily forced past the roller Q when it is desired to start the machine due to the action of the springs U which control the movements of the roller.

Blank sheets of paper W to be impressed are placed upon the table S and forced forward by hand until the end of the paper engages the edge of the projection T, as shown in Fig. 4 in which position the drum C is 105 normally at rest. The drum is then turned forcing the projection T out from under the roller Q which engages the paper W and presses it against the gelatinous surface of the sheet E. The projection T is placed 110

some distance away from the edge of the feeding member O and also away from the edge of the clamp H so that when the feeding member O passes out from underneath the roller Q the upward movement of the feeding member will raise the edge of the paper W as shown in dotted lines in Fig. 4. On the further rotation of the drum the raised edge of the paper is engaged by two stripping rollers X which strip the paper W off the gelatinous strip E.

The stripping rollers X are preferably driven by means of suitable gears Y at the same speed as the periphery of the drum so that the paper W will be drawn off in a uniform manner onto the table a. In order to insure the edge of the paper W being engaged by the stripping rollers X a suitable adjustable guide b is provided as shown in Fig. 4 for accomplishing this purpose.

While the invention has been described with particular reference to the details of construction, the same is not to be considered as limited thereto, as many changes can be made and still fall within the scope of the invention set forth in the following claims.

I claim—

1. A duplicating machine comprising in combination a drum, a sheet of gelatinous material secured to the surface of said drum, a presser roller, a feeding member on said drum arranged to be compressed by said presser roller, and stripping rollers for

stripping the paper off said gelatinous material.

2. A duplicating machine comprising in combination a drum, a sheet of gelatinous material secured to the surface of said drum, a presser roller for pressing the paper in contact with said gelatinous material, stripping rollers for stripping the paper off said gelatinous material, and a feeding member on said drum for feeding said paper into the stripping rolls, said feeding member being arranged to be compressed by said presser roller as it passes under the same.

3. A duplicating machine comprising in combination a drum, a sheet of gelatinous material secured to the surface of said drum, a presser roller for pressing the paper in contact with said gelatinous material, stripping rollers for stripping the paper off said gelatinous material, and a feeding member on said drum for feeding said paper into the stripping rolls, said feeding member being arranged to be compressed by said presser roller as it passes under the same, and means on said feeding member for engaging said roller in starting position.

In testimony whereof I have signed this specification in the presence of two subscribing witnesses.

DAVID HYAMS.
